(57) **CLAIM**

The ornamental design for a bottle lid with a blister package, as shown and described.

DESCRIPTION

FIG. 1 is a perspective view of our new design for a bottle lid with a blister package;

FIG. 2 is a bottom plan view thereof;

FIG. 3 is a top plan view thereof;

FIG. 4 is a cross-sectional view taken in the direction of line 4-4 of FIG. 3;

FIG. 5 is a cross-sectional view taken in the direction of line 5-5 of FIG. 3;

FIG. 6 is a left cross-sectional view of FIG. 4; and,

FIG. 7 is a front cross-sectional view of FIG. 5.

The broken lines illustrate a portion of the bottle lid with a blister package that forms no part of the claimed design.

1 Claim, 7 Drawing Sheets
